CLAIM

The ornamental design for a wear resistant funnel sheet for a material guide chute, as shown and described.

DESCRIPTION

FIG. 1 is a perspective view from above of a wear resistant funnel sheet for material guide chute;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines shown in the drawings represent unclaimed portions of the wear resistant funnel sheet element for material guide chute and form no part of the claimed design.
